UNITED STATES PATENT OFFICE.

THURSTON G. HALL, OF BUFFALO, NEW YORK, ASSIGNOR OF ONE-HALF
TO GEORGE H. VAN VLECK, OF SAME PLACE.

APPARATUS FOR SMELTING ORES.

SPECIFICATION forming part of Letters Patent No. 247,842, dated September 20, 1881.

Application filed August 11, 1880. (No model.)

To all whom it may concern:

Be it known that I, THURSTON G. HALL, of the city of Buffalo, in the county of Erie and State of New York, have invented a new and useful Improvement in Apparatus for Smelting Ore, of which the following is a specification, reference being had to the accompanying drawing.

This invention relates more especially to that class of blast-furnaces in which a gas-blast is employed in connection with an air-blast, and in which the gas is derived in a hot state from a furnace of some kind.

The object of this invention is to prevent the injurious effect of the hot gas upon the blowing apparatus.

My invention consists in providing the gas-conduit with a cooler of the construction hereinafter described, whereby the gas is cooled before it is admitted to the blowing apparatus, as will be hereinafter more fully set forth.

The accompanying drawing represents a sectional elevation of my improved apparatus.

A represents a blast-furnace of any ordinary and well-known construction.

B represents the chimney or other gas-exit passage of a boiler or other ordinary furnace, C, in which coal or other suitable fuel is burned.

D represents the gas conduit or pipe which leads from the gas-exit passage B to the gas-tuyeres e of the furnace A.

F represents a surface-cooler, arranged in the gas-conduit D, between the gas-supply passage B and the blowing apparatus G, which may be of any suitable and well-known construction. As shown in the drawing, the cooler F is composed of a closed vertical tank provided with vertical pipes f, which are fitted in two horizontal plates, g, forming an upper and lower chamber, H I, in the tank F. The gas enters the upper chamber, H, passes thence through the pipes f, and escapes into the lower chamber, I, whence it passes to the blowing apparatus G.

k is a water-supply-pipe, through which cold

water is admitted to the lower part of the space between the heads or plates g and around the pipes f; and l is a waste-pipe, through which the water which has become heated by contact with the hot pipes f is permitted to escape from the top of the water-space. The water which has become heated in its passage through the cooler may be used for feeding the boiler or for any other purpose.

M represents an equalizing-vessel, which may be arranged in the gas-conduit D, between the blowing apparatus G and the tuyeres e. The vessel M is made of sufficient size to receive and retain a large volume of gas, and it is preferably provided with a regulating-valve, n, which is adjusted to blow off when the gas-pressure within the equalizer exceeds a certain desired limit. In this manner a steady supply of gas is furnished to the tuyeres at all times, and the heat of the gas is abstracted before it reaches the blowing apparatus, thereby preventing the gas from interfering with the proper and regular operation of the same.

o represents the blowing apparatus, which supplies air to the furnace by means of the air-tuyeres p, connected therewith, and which may be of any ordinary and suitable construction.

I claim as my invention—

The combination, with a blast-furnace, A, and the gas-exit B of a generating-furnace, 75 of a gas-conduit, D, and blowing apparatus G, whereby the gas is conducted from the generating-furnace to the blast-furnace, and a surface-cooler, G, provided with water supply and escape pipes k l, and arranged in the gas-conduit D, between the generating-furnace and the blowing apparatus, whereby the gas is deprived of its heat before it enters the blowing apparatus, substantially as set forth.

T. G. HALL.
